UNITED STATES PATENT OFFICE.

DENNIS J. GALBRAITH, OF PLAINFIELD, NEW JERSEY.

DESIGN FOR A PIPE-CO尤PLING.

SPECIFICATION forming part of Design No. 30,031, dated January 17, 1899.

Application filed December 14, 1898. Serial No. 699,265. Term of patent 14 years.

To all whom it may concern:

Be it known that I, DENNIS J. GALBRAITH, a citizen of the United States, residing at Plainfield, in the county of Union and State of New Jersey, have invented and produced a new and original Design for a Pipe-Coupling for Washtubs, &c., of which the following is a specification.

In the accompanying drawings, Figure 1 is a side view, and Fig. 2 is a front view.

The leading feature of this design relates to the inclined bend A, in connection with the horizontal portion B and the T-head coupling C.

The horizontal portion B of the coupling is intended to pass through the back of the washtub and to receive into the end of it a faucet, the bend and T-head C of the coupling coming behind the back of such tub.

I claim—

The design for a pipe-coupling substantially as described and shown.

Signed by me this 8th day of December 1898.

DENNIS J. GALBRAITH.
